UNITED STATES PATENT OFFICE.

AMOS CALLESON, OF BROOKLYN, NEW YORK.

BOTTLE FILLING AND SEALING MACHINE.

Application filed June 25, 1923. Serial No. 647,468.

This invention relates to bottle filling and sealing machines, and its object is to provide a simple and durable machine of this class in which the filling and sealing may be effected with the maximum of speed and without requiring any greater skill on the part of the attendant beyond feeding the empty bottles to a conveyor and removing them therefrom as fast as they are filled and sealed.

Among the principal features of the machine are a novel combination of parts whereby a sealed filling space may be formed at the container mouth and the filling liquid then delivered to the container; a novel construction of a machine of the rotary type for filling or sealing or otherwise operating on containers whereby the same may be altered to suit containers varying as to standards of height; novel means for detecting the presence of a container as a preliminary to performing a filling operation or the like; and a novel combination of parts whereby adjustment to suit different heights of containers may be effected and whereby compensation may take place for containers varying in height though supposed to be of the same height-standard.

Fig. 1 is a vertical sectional view of the machine, partly in side elevation;

Figs. 2 and 3 are horizontal sections on lines 2—2 and 3—3, respectively, of Fig. 1;

Fig. 4 is a front elevation of the upper turret of the main rotary structure, certain parts carried thereby appearing in section and others in elevation;

Fig. 4^a is a fragmentary view of the valve-depressor and its controlling means;

Fig. 5 is a fragmentary section of said turret on line 5—5, Fig. 4, showing those of said parts below said line in elevation and those above said line removed;

Fig. 6 is a side elevation of said parts and a fragment of said turret;

Fig. 7 shows in front elevation the lower turret, the lower fixed cam (said turret being broken away to reveal the cam) and a part of one of the container supporting means;

Fig. 8 shows in plan, partly in section, what appears in Fig. 7;

Fig. 9 is a sectional view, in a plane radial with respect to the axis of the rotary structure, of the turret, cam and container supporting means, illustrating particularly the mechanism for compensating for differing heights of containers;

Fig. 10 is a plan of the bottle rest;

Fig. 11 shows in vertical section the parts immediately concerned in the operations of filling and closure-affixing, and a bottle and crown or closure in the positions they occupy just prior to the filling operation;

Figs. 12 and 13 are a plan and front elevation, respectively, of a certain sleeve shown in Fig. 11; and

Figs. 14 to 15^a illustrate the cams e. g.

The frame of the machine may be described as follows: In a cylindrical base *a* are stepped and fixed three pillars *b* which have slidably vertically thereon the head *c* of the frame. Upstanding centrally from the bottom of and within the base is a pedestal *d*, which has suitably affixed thereto a cam *e*. A vertical shaft *f*, which is splined in the pedestal *d* at *f'* and hence may be moved vertically but cannot rotate, has affixed thereto another cam *g* and through the intermediary of a gear *h* interposed between this cam and the head *c* the said head is supported. Thus when the shaft is adjusted vertically the effective height of the frame is altered, as well as that of the rotary structure to be described. Such adjustment may be effected by a vertical screw *i* which is tapped into the shaft's lower end and is swiveled in a bracket *j* in the base, the screw and a suitably journaled horizontal shaft *k* being connected by bevel gearing *l* whereby to turn the screw upon turning shaft *k*, as by a handle *m*. (There may be anti-friction bearings, indicated at *n* in Fig. 1, between the gear *h* on the one hand and cam *g* and head *c*.)

The aforementioned rotary structure includes two turrets, upper and lower, splined to rotate together about the shaft *f* as an axis, the lower one being journaled on the lower or fixed part of the frame of the machine and the other including the gear *h* and thus adjustable vertically with the parts *f*—*c* of the frame. The lower turret, *o*, is a generally cylindrical casting having as a rigid part thereof a central pedestal *o'* which is stepped and journaled at *p* on the top of the pedestal *d*; it also has four equidistant upwardly open pockets *o*². The upper turret is a generally cylindrical casting *q* having the gear *h* forming the top thereof (Fig. 4) and having at its lower end a hub *q'* which is splined at *q*² on the upper end of the pedestal *o'*. The upper turret *q* houses the cam *g*. The structure *o*—*q* is adapted to be rotated

from a motor r or other suitable means through a gear s journaled on the head c and having a bevel pinion t which meshes with a bevel pinion u on a vertical shaft v , also journaled in the head, said shaft having a pinion w which meshes with the gear h forming a part of said rotary structure. However, it is entirely immaterial by what means the rotary structure is rotated.

Within the base a and in vertical alignment with each pocket o^2 (formed in a depressed marginal part of the turret o) is a carrier x (Figs. 1, 7, 8 and 9) having a roller x' which runs in the peripheral groove e' of the cam e . This carrier (Fig. 7) is guided in a slot o^5 in the turret and is penetrated by the squared portion (Fig. 8) of a stem or spindle y adapted to slide vertically in the carrier and having a depending trunnion y^2 guided in a bearing o^3 at the lower end of the turret o and an upstanding trunnion y^3 pinned or otherwise fixed in the depending tubular stud z' of a bottle-rest z whose said stud is guided in a bearing o^4 of the said turret. z^2 is the bottle pad or cushion of the bottle-rest. Any means well known in the art is employed to frictionally resist the vertical movement of the plunger formed by the bottle-rest and its stem y relatively to the carrier; in Fig. 8 this is shown as a pair of friction plates 2 held bearing against opposite sides of the squared part of the stem y by springs 3 interposed between the friction plates and set screws 4. In a vertical and radial slot y' of the squared part of the stem is fixed by a pin 5 a block 6 having an underneath downwardly and inclined stepped surface 6^a . The carrier also has a vertical and radial slot 7 on the floor or lower end surface of which slides a block 8 having an upper and downwardly inclined stepped surface 8^a to engage the surface 6^a of block 6, the block 8 acting as a wedge. A spring 9, coiled about a pin 10, projecting inwardly from a plate x^2 which covers the carrier slot 7 and is suitably affixed to the outer face of the carrier, normally holds the block 8 inwardly (Figs. 1 and 9). At a suitable point in each revolution of the rotary structure the block 8 is shifted radially outwardly so that, being clear of the block 6, the bottle supporting plunger y can be depressed in the carrier subject to the resistance of its friction grip means already described. This is accomplished by a hump or projecting cam surface e^2 on the periphery of the cam e below its cam groove e' encountering the inwardly projecting heel 8^b of the block (Figs. 7, 8 and 9). As soon as the hump e^2 clears the block the latter returns under and in position to prevent further downward yield of the plunger, as during closure affixing. As will appear, the bottle supporting means just described (in-

cluding the carrier and plunger) is adapted for compensating for differing heights of bottles of the same height-standard; it may be here stated that after the compensating has been effected and when the carrier performs its next downward stroke under influence of the cam e the plunger is returned to its normal elevation in the carrier by contact of the bottle rest with the top of the bearing o^4 (see at the left of Fig. 1).

Secured to the turret q in vertical alignment with each bottle pocket o^2 of turret o is an annulus 11 (Figs. 1, 4 to 6 and 11) which has screwed on its lower end a mouth-piece 12 affording a ledge to support a yielding rubber gasket 13 contained in the annulus.

A tubular structure forming a part of what I term a slide telescopes this annulus and coacts to form therewith a sealed filling head. This structure includes the tubular stem 14, the sleeve 15 which is slipped over the reduced lower end of the stem 14 and is secured thereto, as by the screw or pin 16 shown in dotted lines in Fig. 4 (which sleeve will be further described in detail), and a ring 17 which is screwed onto the stem above the sleeve 15. A yielding rubber gasket 18 is received in an underneath groove in the ring 17 and embraces the parts 14 and 15, and at a certain point in the operation when the mentioned structure is depressed the gasket 18 is compressed between 17 and 11 while the gasket 13 is compressed between the lower end of 15 and the mouth-piece 12. A part of the said slide is a block 20 to which structure 14 is secured by screws 19 and which moves in a vertical slot q^3 in the turret q and is guided by gibs 21 on the turret engaged in lateral grooves in the block. The block has a roller 22 which travels in the peripheral groove, g' , of the cam g . The lower end of the stem 14 has an internal ledge 14^a on which is seated and rigidly held in place by a screw 23 a collar 24, with a gasket 25 interposed between the collar and ledge; and down against this collar is normally held an inverted cup 26 subject to the pressure of a spring 27 interposed between the collar and a plug 28 (Figs. 3 and 4) screwed into the top of the body part 14.

A cap plunger 29 is arranged in said tubular structure, protruding from the lower end of the stem 14 into the sleeve 15 and having a collar 29' housed within the cup 26 and of less depth than the same, so that the plunger has some movement vertically independently of the cup. The upper end of this cap plunger protrudes through the plug 28 and has a collar 30 fixed thereon and formed with a flat face 30^b to bear against the face of block 20 to keep the cap plunger from turning.

The lower end of the sleeve 15 has an

inward annular enlargement 31 forming an annular chamber 32 and also affording at 33 a ledge for a closure B, the sleeve having a lateral opening 34 to admit the closure to said ledge. 35 is simply a back stop to prevent the admitted closure from moving beyond the ledge. 36 (Fig. 1) is suitable means for feeding the closures to the opening 34, the same being carried by the frame 10 of the machine and adapted to feed closures one after another to the openings 34 as they pass. The chamber 32 of sleeve 15 has an induction opening 37 (Figs. 11 and 12) for admitting liquid thereto and adapted to register with a liquid supply port 38 (Fig. 4) in the annulus 11 when the sleeve has been fully depressed; it also has a series of inward and downwardly deflected eduction openings 37^a. Just above the ledge 33 the sleeve has an eduction opening 39 adapted to register with a snifting port 40 (Fig. 4) in the annulus 11 when the sleeve is fully depressed. (It may be here stated that the closure is admitted when the slide or main 20 plunger is in the position shown in Figs. 4 and 6, or elevated, and when the slide is fully depressed to bring duct 37 into registry with port 38 and the chamber-forming enlargement 31 below the snifting port 40 25 the closure-admitting opening 34 will be contained within the annulus 11 so that, as will appear, 34 will then be housed within a sealed space and no escape of pressure to the atmosphere can then occur through said 30 opening.) 15 forms in effect a valve.

By means of depending plate springs 41 secured at their upper ends between the sleeve 15 and the reduced lower end of the stem 14 diametrically opposite blocks 42 are 40 yieldingly held in the position shown in Fig. 11, their inner ends being beveled at top and bottom; the upper part of the enlargement and the sleeve 15 are cut away at 43 to accommodate the pawls formed by the blocks 45 and springs and allow their outward movement, as when a closure admitted to the ledge is then forced upwardly, wedging the pawls apart and assuming the full line position shown in said figure. Above these 50 blocks and supported by the enlargement is a closure-affixing appliance 44 which may be of the type set forth in my Patent No. 1,353,628. It is interposed between said enlargement and the lower end of the stem 14. 55 The duct 38 leads from a valve chamber 46 projecting from the side of the annulus 11, and this valve-chamber is supplied with the filling liquid through a pipe 47 which extends up through the gear h and then radially inward, communicating with a vertical pipe 48 (Fig. 1) which turns with the gear and may communicate in any way with a suitable source of liquid supply. The valve chamber has a valve 49 normally held 60 closed by a spring 50 (Fig. 4) and adapted

to be opened by downward pressure applied to its upper protruding end. The valve depresser consists of a stem 51, arranged to rock on a vertical axis in a bearing 52 projecting from the side of the stem 14, and a 70 foot 53 on the lower end of the stem 51; the upper end of the stem carries a lever 54, one arm 54^a of which is connected by a spring 55 with a fixed point on the slide (Fig. 3) and is thus normally held by the spring 75 against the side of the collar 30 and the other arm 54^b of which projects outward and is adapted to impinge a fixed abutment 56 on the frame of the machine in the rotation of the rotary structure. Arm 54^a has an inside bevel 54^c.

An arm 57 (Figs. 4 and 5) projects laterally from the annulus 11 and has a passage therethrough of which the port 40 forms its terminus, said passage forming a gas-relief duct and a liquid drain. This arm carries at its free end an air retreat chamber 58 which communicates at the bottom with the passage of the arm (all of this chamber except its base, which is integral 80 with the arm, is removed in Fig. 5), and in this chamber is a piston 59 adapted to be adjusted to different elevations to change the capacity of the chamber, as by having holes 60 in its stem any one of which may receive a pin 61 removably arranged in the chamber. The base of the chamber has a snifting vent 62 normally closed by a spring-pressed valve 63 which is adapted in the rotation of the rotary structure to encounter 90 a fixed abutment 64 to be opened thereby.

The bottles may be fed to the machine as shown in Fig. 2. Here 65 is a belt or conveyor moving along a runway 66 arranged tangentially with respect to the turret o and 105 so that the surface of the conveyor is flush with that of the depressed marginal part of the turret, the runway having a bottle outlet 66^a and a bottle inlet 66^b separated by a deflector 67 which switches the bottles one 110 after another onto the turret and onto the bottle-supports z and, after they have made the circuit of the filling and sealing machine and become filled and sealed, back onto the conveyor. 115

The top of block 20 is shown recessed at 69 to receive a dog 70 pivoted on a pin 71 in a bracket 72 which may be secured to the gear h by a screw 68, the dog 70 having a portion (as a roller) 73 to run on the top 120 of the cam g which has a rise at g^2 (Figs. 1 and 6). The weight of the dog tends to tilt it outward so that it may abut the slide at 74, Fig. 6, at the bottom of a slot therein through which it projects (see Fig. 1 at the right) and during a part of the rotation assume the upward thrust thereof, as during the gasket compressing and sealing, as will appear; but at a certain point in the revolution of the rotary structure the cam rise g^3 . 125

by acting on the roller 73, retracts the dog (see Fig. 6), allowing the cam to raise the slide.

- The operation will be described with reference to Figs. 14 to 15^a which show the two principal cams *g* *e* divided upon radial lines in substantially coinciding sectors: The sectors of the cams corresponding to the fully elevated and depressed positions of the slide and carrier, respectively, are marked I—I in these figures. In the period represented by these sectors a bottle is placed on the bottle support and a closure fed to the ledge 33, and at this time the dog 70 is held retracted by its camway *g*². In sectors II—II the slide is depressed into contact with gasket 13 and remains there for a while and meanwhile the carrier is elevated to cause the bottle to raise and thus position the closure on pawls 42, allow the depressor to assume operative relation to valve 49 by the incidental rise of the cap plunger 29 and its collar 30 to clear lever arm 54^a (Fig. 4^a), and effect compensation, and then returns to position the bottle mouth in said gasket, whereupon the slide descends further to compress the gasket around the bottle mouth and establish the ports for the flow of liquid and an escape of air from the bottle and, of course, cause the depressor to open the valve 49. In sectors III—III the cam *g* is relieved of all upward thrust by the dog 70 being allowed by cam *g*² to dog the top of the slide, and the carrier and slide remain at standstill for the major part of the cycle while the bottle is filled. Near the end of the period represented by these sectors the arm 54^b of the depressor engages the abutment 56, turning the depressor so that valve 49 is free to rise, thus closing the passage of pipe 47 and holding depressor arm 54^a from under collar 30. (It will be understood that the filling automatically ceases when the pressure in the space formed by the filling head, chamber 58 and the bottle balances that in the source of supply). In sectors IV—IV the carrier rises for closure-affixing (after which pawl 70 runs off camway *g*², so that the slide is again free to rise) and then falls to its initial level, while the slide at first remains at standstill and then rises to its initial level to release the gasket 13 and hence the bottle therefrom so that the latter can descend with the carrier; of course when the slide rises the depressor clears valve 49 and if, on the reseating of the cup 26 with consequent ejecting of the closed bottle from the affixing appliance, the plunger 29 has not already fallen to interpose collar 30 against the depressor swinging into its superposed or operative relation to the valve the plunger when it does fall will by said collar wiping against the bevel or cam surface 54^a swing the depressor to its inoperative relation to said valve,

the depressing of the plunger being insured in any event by its impinging against screw 68.

It will be noted that during the filling period the filling liquid enters the chamber 32 and is delivered therefrom in opposite downwardly inclined jets (which if desired may be directed so that the liquid forms a vortex in the mouth of the bottle) while the air expelled from the bottle by the liquid passes up through the mouth of the annular enlargement 31 of sleeve 15 and then via ports 39 and 40 to chamber 38, the closure having been elevated above its seat at 33 so as to offer no obstruction to the escape of the air in this way.

At any time after the bottle mouth is sealed by contact with the closure in the closure-affixing stroke of the carrier the lever 63 may encounter the stop 64 and be moved thereby to cause venting of the chamber 59.

The principal reason for employing the means 70 to oppose the upward yield of member 14 once the cam *g* depresses it is to save the wear and tear which would otherwise result from parts (as *g* and 22) moving in contact with each other at this time, not only the bottle but the gaskets 13 and 18 being factors acting to cause such yield; I claim this means, however, with reference to its thus indicated two functions independently of each other.

In previous filling machines having a chamber, as 58, to receive the air and other gas contained in the bottle and thus allow complete filling thereof without interruptions for snifting, the construction was not such as to permit free return of the liquid to the bottle which is sprayed into the chamber when the filling takes place; in short, in previous machines the construction discouraged free return of the liquid, with the result that there was an appreciable loss of the liquid and the machine was always wet and untidy. It will be noted that in my machine the connection 39—40 between the filling head and chamber is not only commodious in size but that it rises directly (though at an incline) from the filling head and continues such rise clear to the chamber, without any surfaces or obstacles to check the prompt return of all liquid accumulating therein or in the chamber, so that all the liquid drains back freely into the bottle. Moreover, where as here the machine is adapted also for affixing a closure to the container after the filling, according to my invention the parts cooperating in the affixing, as the affixing appliance itself, the supporting ledge or equivalent for the closure and the plunger 29, are arranged above the delivery or lower end of said connection or passage 39—40, so that they do not interfere with this return of the liquid.

Having thus fully described my invention,

what I claim as new and desire to secure by Letters Patent is:—

1. Means for conducting liquid into a container including, in combination, an apertured gasket-compressing member, an annular elastic gasket having underneath support in said member, said member having a liquid-delivery outlet leading to the aperture therethrough, and a gasket-pressing member arranged in the aperture of the first member and above the gasket, one member being movable telescopically relatively to the other to compress the gasket between them into constricting relation to the mouth-portion of a container placed in the gasket and the second member having means, adapted to communicate with said outlet upon such compression of the gasket, for conducting liquid through itself to said aperture.
2. Means for conducting liquid into a container including, in combination, an apertured gasket-compressing member, an annular elastic gasket having underneath support in said member, said member having a liquid-delivery outlet leading to the aperture therethrough, and a second gasket-pressing member having as its base an annular chamber-portion telescopically arranged in the aperture of the first member and above the gasket, one member being movable telescopically relatively to the other to compress the gasket between them into constricting relation to the mouth-portion of a container placed in the gasket and the second member having an inlet to its chamber adapted thereupon to communicate with said outlet and also having an outlet from said chamber to the opening therethrough.
3. Means for conducting liquid into a container including, in combination, an apertured gasket-compressing member having a fluid conducting port leading to the aperture therethrough, an annular elastic gasket having underneath support in said member, and a second gasket-pressing member telescopically associated with the first member above the gasket, one member being movable telescopically relatively to the other to compress the gasket between them into constricting relation to the mouth portion of a container placed in the gasket, and the second member forming a valve for controlling the fluid flow through said port.
4. Means for conducting liquid into a container including, in combination, an apertured gasket-compressing member having a liquid conducting port leading to the aperture therethrough, an annular elastic gasket having underneath support in said member, and a second gasket-pressing member telescopically associated with the first member above the gasket, one member being movable telescopically relatively to the other to compress the gasket between them
- into constricting relation to the mouth portion of a container placed in the gasket, and the second member forming a valve for controlling the liquid flow through said port and having an air-escape opening opposite the opening in the gasket.
5. Means for conducting liquid into containers including, in combination, an apertured gasket-compressing member, an annular elastic gasket having underneath support in said member, and means to form with said member, the gasket and a container having its mouth-portion introduced into the gasket a sealed space, the latter means including another gasket-pressing member telescopically associated with the first member above the gasket and another elastic gasket arranged to be compressed between said members independently of the first gasket, one of said members being telescopically movable relatively to the other to compress the gaskets.
6. In a machine for filling and thereupon affixing a closure to a container, the combination of means to receive the container mouth-portion, means, telescoped in the first means, for forming therewith and with the so-received container mouth-portion a sealed space, and a closure-affixing appliance in the second means, said second means having a closure admitting opening exposed to the atmosphere and one of said means being movable telescopically relatively to the other to house said opening in the first means and form with said second means such sealed space.
7. In combination, a hollow structure to house a container mouth-portion, the same having a bottom container-mouth-portion-receiving opening and above the opening means on which to support a closure in primary position and above said means means to support the closure in secondary position, and a closure-affixing appliance in said structure above the second means, said structure also having means to conduct a filling liquid to its interior and, between the first two means, an air-escape outlet, and the container and said structure being movable one relatively to the other first to cause the container to shift the closure placed on the first means to the second means, then in the opposite direction to permit filling and escape of air at the outlet, and then to cause the container to move the closure into position to be affixed to the container by said appliance.
8. In combination, a hollow structure to house a container mouth-portion, the same having a bottom container-mouth-portion-receiving opening and above the opening means on which to support a closure in primary position and above said means means to support the closure in secondary position, a closure-affixing appliance in said structure

above the second means, the container and said structure being movable one relatively to the other to cause the container to shift the closure placed on the first means first to the second means and then into position to be affixed to the container mouth-portion by said appliance, and a normally depressed and upwardly yielding plunger arranged to be elevated by the closure when shifted from the first to the second means.

9. The combination of two structures arranged one within the other and one being revoluble relatively to the other around an axis extending through the inner structure and one being an actuating structure having a camway and the other a carrier structure, pressure members to compress a container between them arranged in the carrier structure and one of which is movable therein toward the other lengthwise of said axis and adapted to be engaged by said camway and moved thereby in the carrier structure on revolving one of said structures relatively to the other, and means, movable into interposition between the carrier structure and the movable member after its movement toward the other member and consequent compressing of the container, to oppose return movement of the movable member.

10. The combination of two structures arranged one within the other and one being revoluble relatively to the other around an axis extending through the inner structure and one being an actuating structure having a camway and the other a carrier structure, means on the carrier structure to form with the container a sealed space including a compressible gasket and a gasket-pressing member movable to compress the gasket between itself and the carrier structure and adapted to be so moved by the camway on movement of one of said structures relatively to the other, and means, movable into interposition between the carrier structure and said member after its movement to cause compressing of the gasket, to oppose return movement of said member.

11. In combination, a passaged structure whose passage is adapted to deliver a liquid to a container operatively positioned to receive liquid from the discharge end of the passage, a valve in said structure normally closing the passage, a carrier structure,

means movable in the carrier structure into and out of position to open the valve, one structure being rectilineally movable relatively to the other to cause said means to open the valve, and means, movable in the carrier structure by the container, for controlling the position of the first means.

12. In combination, a passaged structure whose passage is adapted to deliver a liquid to a container operatively positioned to receive liquid from the discharge end of the passage, a valve in said structure normally closing the passage, a carrier structure, and means movable in the carrier structure into and out of position to open the valve, one structure being movable relatively to the other to cause said means to open the valve, said means being movable in the carrier structure around an axis substantially parallel with the path of movement of the movable structure.

13. In combination, a passaged structure whose passage is adapted to deliver a liquid to a container operatively positioned to receive liquid from the discharge end of the passage, a valve in said structure normally closing the passage, a carrier structure, means movable in the carrier structure into and out of and normally urged into position to open the valve, one structure being movable relatively to the other to cause said means to open the valve, and means, normally resisting movement of the first means into said position, movable by the container to allow such movement of the first means.

14. Apparatus for conducting liquid into a container including, in combination, an apertured container-mouth-receiving member having a liquid delivery outlet leading to its aperture and around its aperture an internal gasket supporting ledge, and means, including an elastic annular gasket on said ledge and a gasket compressing member co-active with the ledge to compress the gasket, for forming with a container whose mouth is inserted in the gasket a sealed space within the first member, said means normally closing the outlet and having a port adapted upon compression of the gasket and the forming of said sealed space to connect the outlet with said space.

In testimony whereof I affix my signature.

AMOS CALLESON.
